COMBINED ATOMIZING AND VAPORIZING TORCH

Seddon C. Nelson, New York, N. Y., assignor to
 Hauck Manufacturing Company, Brooklyn,
 N. Y., a corporation of New York

Application July 23, 1936, Serial No. 92,094

2 Claims. (Cl. 158—79)

The invention relates to burner apparatus for liquid fuel, more especially oils and the like which, when utilized for combustion in a vaporizing burner, require the provision of preheating means to insure the vaporization of the fuel and involving a substantial time interval before the fuel may be ignited.

It is an object of the present invention to provide a vaporizer type of torch wherein such preliminary heating is not required; and with which the fuel may be ignited immediately to set the burner in operation, there being required no wick or like means for preheating purposes.

15 Another object of the invention resides in the provision of fuel atomizing means utilizing air in connection with the burner nozzle for starting up of the burner, together with a vaporizing coil adapted temporarily to receive and to heat 20 the air effecting atomization.

A further object of the invention resides in the provision, in a burner having the usual vaporizing coil, of means whereby the interior of this coil as well as the burner nozzle will be 25 maintained substantially free of carbon deposits.

In carrying out the invention, there is associated with the usual form of vaporizing burner embodying a burner head with vaporizing coil and a nozzle member from which the vaporized 30 fuel is injected into the burner head, a valve member embodying a single valve with oppositely disposed valve pieces respectively adapted to cooperate with two seats, the valve in one position controlling the delivery of air into the 35 aforesaid preheater coil and in the other position the delivery of oil thereto.

The usual nozzle member is modified also to the extent of adapting it for atomizing purposes by the addition of an oil injector spud mounted 40 therein and having an orifice axially aligned with the nozzle orifice. This modified nozzle member affords initially a means for atomizing the fuel which is delivered through the orifice of the injector spud to be atomized; and subsequently 45 when fuel is delivered thereto through the coil to inject the vaporized fuel into the burner head, the injector spud then being substantially inactive.

The nature of the invention, however, will best 50 be understood when described in connection with the accompanying drawing, in which:

Fig. 1 is a longitudinal section through the novel burner apparatus.

Fig. 2 is an end elevation thereof.

55 Referring to the drawing, 10 designates a cas-

ing affording a burner head or hood with outlet or mouth 11 at its outer end and with an inlet opening 12 at its inner end into which the fuel in finely divided state or in vaporized condition is to be delivered for combustion as hereinafter 5 set forth. There is mounted within the said casing toward its outlet end a preheater coil 13, the outer end thereof being connected by pipe 14 to a hot air or vapor duct 15 of the nozzle portion of the burner. The latter comprises a body portion 16 axially bored to receive an inlet pipe 17 for the liquid fuel and also an injector spud or primary nozzle member 18 communicating with the bore and having the orifice 19 through which oil is delivered. About the orifice 15 end of the spud 18 there is removably secured a further or secondary nozzle element 20 provided with an orifice 21 axially aligned with the orifice 19, but of larger diameter, and directed toward and in the axis of the inlet opening 12 to the 20 burner head.

Body 16 is, furthermore, provided with a bypass duct 22 which communicates with the bore thereof and terminates in a valve seat 23. With the latter is designed to cooperate a valve piece 25 24 of a valve member movable in a chamber 25 which is adapted to communicate with duct 22 through the seat 23 and having the further and oppositely disposed seat 26. This latter seat is designed to cooperate with an oppositely disposed valve piece 27 of valve member when brought in contact therewith as through manipulation of the hand wheel 28 of the valve.

The double-ended valve member is reciprocable in the valve chamber 25 which is also in communication with the inner end of the preheater coil, as through the pipe 29; and a further duct 30 is designed to supply air for atomization and under the requisite pressure to chamber 25 from a chamber 31 located beyond the valve seat 26. 35 When the inner of the valve pieces seats to close off the duct 22, the oppositely disposed one 27 will be unseated and communication is afforded between the source of air supply and the coil 13. From the latter, in turn, air under 40 pressure is afforded about the spud 18 and through orifice 21 for atomizing oil delivered through the orifice 19, so that the burner may be immediately started by igniting the 45 discharged atomized fuel.

As soon as the combustion of the fuel has brought the coil 14 to the temperature required for vaporization of oil, hand wheel 28 is manipulated to gradually unseat the valve piece 24 for admitting the fuel through duct 22 into the 50 55

valve chamber 25 and from the same through pipe 29 into the vaporizing coil 13. At the same time, the supply of air is gradually cut off until valve piece 27 finally contacts its seat 26 to shut the same off entirely. The burner then operates in the usual manner as a vaporizing torch.

It will be appreciated that in the passing of air through the coil 13, not only will this air serve to burn any deposits of carbon and thus keep the interior of the coil clean; but the introduction of heated air through the duct 15 and pipe 14, which connect the coil to the nozzle 20 when the fuel is eventually provided through the said coil, will insure against the vapor being chilled and condensed in its passage from the coil to the nozzle. Proper combustion will, therefore, be maintained during the transition from the atomizing action to the vaporizing action.

I claim:

1. In burner apparatus: the combination with a burner head provided with an inlet and a mouth, and a heating coil mounted in the head; of a nozzle element embodying an inner and an outer orifice axially displaced for directing fuel axially into said burner head inlet, a fuel connection to the nozzle element, a source of air supply, means for connecting the latter to one end of the heating coil, means connecting the other end of the said coil to the nozzle element for discharge through the outer of its orifices only, and a duplex valve member adapted to

communicate with the said fuel connection and with the said source of air supply to afford alternatively air or fuel to the said heating coil and through the same to the nozzle element.

2. In burner apparatus: the combination with a burner head provided with an inlet and a mouth, and a heating coil mounted in the head; of a nozzle retaining body bored to receive a fuel connection, a nozzle element communicating with the bore and having an outlet orifice, a secondary nozzle element mounted about the first-named nozzle element and provided with an orifice in the axis of the first-named nozzle for discharge of fuel into said inlet, said secondary nozzle element communicating with the outer end of the coil, and the said body being provided with a by-pass duct communicating with the bore thereof and said duct terminating in a chamber affording oppositely disposed valve seats, a valve member operating in said chamber having oppositely disposed valve pieces adapted to cooperate respectively with the said seats, there being provided beyond the seat opposite the by-pass duct a further chamber adapted for connection with a source of air under pressure and the first-named chamber being in communication with the inner end of said coil whereby air or fuel may be delivered into said coil as the valve pieces seat on one or the other of the respective seats.

SEDDON C. NELSON.
